CLAIM

We claim the ornamental design for a pourer, as shown and described.

DESCRIPTION

FIG. 1 is a top isometric view of one embodiment of a cap for a pourer showing our new design in closed position further including an environment (environment not claimed);

FIG. 2 is a top view thereof, shown in a closed position; FIG. 3 is a front view thereof; FIG. 4 is a bottom view thereof; FIG. 5 is a right side view thereof; FIG. 6 is a rear side view thereof; FIG. 7 is a left side view thereof; FIG. 8 is a cross-sectional view thereof divided along the line 8-8 shown in FIG. 2; FIG. 9 is a top view thereof, shown in an open position; and, FIG. 10 is a cross-sectional view thereof divided along the line 10-10 shown in FIG. 9.
